DESIGN FOR A MUSICAL INSTRUMENT MOUTHPIECE

Josephus Thompson, Covington, Ohio, assignor of
one-third to Grossman Music Company, Cleve-
land, Ohio, a partnership composed of Julius I.
Grossman and Henry S. Grossman

Application April 4, 1945, Serial No. 118,858

Term of patent 14 years

(Cl. D56—1)

To all whom it may concern:

Be it known that I, Josephus Thompson, a citizen of the United States, residing in the city of Covington, county of Miami, and State of Ohio, have invented a new, original, and ornamental Design for a Musical Instrument Mouthpiece, of which the following is a specification, reference being had to the accompanying drawing, forming a part thereof.

Figure 1 is a side elevational view of a musical

instrument mouthpiece showing my new design;

Figure 2 is a plan view thereof;

Figure 3 is a rear end elevational view thereof;

Figure 4 is a front end elevational view thereof;
and

Figure 5 is a bottom view thereof.

I claim:

The ornamental design for a musical instrument mouthpiece, substantially as shown.

JOSEPHUS THOMPSON.
